W Webster,
Sash Balance.

No 16,559.

Patented Feb. 3, 1857.

UNITED STATES PATENT OFFICE.

WILLIAM WEBSTER, OF MORRISANIA, NEW YORK.

MODE OF HANGING WINDOW-SASHES.

Specification of Letters Patent No. 16,559, dated February 3, 1857.

To all whom it may concern:

Be it known that I, WILLIAM WEBSTER, of Morrisania, in the county of Westchester and State of New York, have invented an 5 Improved Method in Attaching the Cords to Window-Sashes Without Removing them from Out of the Frame or Their Places; and I do hereby declare that the following is a full and exact description of the same, 10 reference being had to the accompanying drawing, which makes a part of this specification.

The nature of my improved method consists in making openings or holes into or 15 through the face or exposed part of the sash sufficiently large to admit of the knot made in the end of the cord, and after the knot has been pressed into its place in the opening or hole I then cover over the knot and 20 opening by a thin piece of metal or its equivalent, which may be made with a screw thread on its edge screwed into the opening or hole.

To enable those who are skilled in the 25 manner of attaching cords to window sashes, I will refer them to the accompanying drawing which represents a face view of the frame A and sash B which are or can be made in any of the common ways.

30 C, C are the openings or holes (one being covered over) made in the face part of the sash; they can be made on the opposite side or entirely through if necessary.

D, D are the weights to which are attached one end of the cords E, E; the 35 other end is put over the pulleys F, F, and down through the grooves (which are shown by the dotted lines G, G) into the openings or holes (C, C,) (one not shown) which are made sufficiently large to admit of a knot 40 when made in the cord. After the knots have been put into the holes or whatever it may be to hold the cord from being pulled out of the sash I propose covering over the holes flush with the face of the sash. 45

In this manner of attaching cords or hanging the sash after the cords have been broken, it will be perceived can be done without removing the sash from the frame or out of its place, thereby avoiding taking 50 out of the parting bead or strips, which after the frames have been painted several times is very difficult and tedious and sometimes it is necessary to cut them loose to extricate them, which by my method or improvement it is entirely overcome. 55

What I claim as my invention and desire to secure by Letters Patent is—

The constructing of window sash with 60 holes C, C on their inner face in connection with the holes and grooves G, G as in the manner herein described.

WILLIAM WEBSTER.
